UNITED STATES PATENT OFFICE.

WILLIAM F. AMBACH, OF WOONSOCKET, RHODE ISLAND.

CLOTH-SHEARING MACHINE.

SPECIFICATION forming part of Letters Patent No. 763,835, dated June 28, 1904.

Application filed May 19, 1902. Serial No. 107,920. (No model.)

To all whom it may concern:

Be it known that I, WILLIAM F. AMBACH, a citizen of the United States, residing at Woonsocket, in the county of Providence and State of Rhode Island, have invented a new and useful Improvement in Cloth-Shearing Machines, of which the following is a specification.

In cloth-shearing machines the cloth is supported on the usually rounded edge of the cloth-rest and is operated on by the usually revolving cutters.

The object of the operation is to shear the raised nap and produce a uniform even surface on the cloth. The cloth is under tension as it passes over the cloth-rest, and any local irregularity in the weave of the cloth, such as a knot, will bring the surface of the cloth at this particular point closer to the shearing-knives and cause the nap to be cut closer than at other parts of the surface. Practical experiments to overcome these defects in the cloth by the use of cushions made of rubber or similar elastic material have demonstrated that these do not overcome the defects, because the material of such cushions does not yield locally to the knots, but forms a somewhat extended dished depression which appears in the sheared nap as a raised spot. I have, however, found that with a cushion formed of felted fiber interposed between the cloth-rest and the cloth knots and other imperfections in the weave will cause the cushion to yield locally, so that an even surface of the cloth is maintained and the nap is shown evenly, presenting a finished surface.

I have illustrated in the accompanying drawings the construction of my improved cushion and its use in connection with a cloth-rest substantially like those shown in Patents Nos. 634,602 and 634,603, dated October 10, 1899, for a rest for cloth-shearing machines. I do not wish to confine myself to any particular form of cloth-rest or the particular form of cushion herein described.

Figure 1 is a sectional view of a cloth-rest for cloth-shearing machines provided with my improved cushion. Fig. 2 is a transverse sectional view of an apron provided with my improved cushion. Fig. 3 is a perspective view of the apron.

In the drawings, *a* indicates a sheet of felt

formed by felting fibrous material into a sheet of uniform thickness. In the preferred form the sheet of felt *a* is secured between the folded sheet *b* of cotton cloth forming the apron *B*, the fold of which is secured to the rod *b'* by means of the clamps *b²* *b²*. The clamps serve to hold the sheet on the rod and also engage the sheet *d* as it travels over the cloth-rest. The apron *B* extends from the rod *b'* over the cloth-rest and around the nose *B²* of the same, being held in position by the sheet of cloth *d*, usually smoothly finished silesia cloth, extending from the roll *D* over the apron *B* to the roll *D'*. The cloth *c* to be sheared is indicated by a broken line. The shearing-cutter *E* is indicated in broken lines, as is also the shearing-blade *F*.

The felt used is preferably made of short fiber. The sheet may be of such thickness as will best support cloth of the weight required to be sheared. The felt may be made of any desired density, so as to form a more or less yielding cushion. The felt cushion when used on a cloth-shearing machine differs in its action from rubber or similar cushions in that knots or imperfections in the weave of the cloth depress the cushion locally, because the fibers of the felt yield laterally and support the cloth close up to the knot or imperfection in the weave, thereby insuring the even cutting of the nap and uniform finish of the cloth.

Having thus described my invention, I claim as new and desire to secure by Letters Patent—

In a cloth-shearing machine, the combination with a cloth-rest, of a rod, a sheet embracing the rod and having its ends extending over the cloth-rest, a felt cushion interposed between the sections of the sheet over the cloth-rest, clamps partially encircling the rod over which the sheet is passed and a cloth bearing against the clamps and extending over the sheet, substantially as described.

In testimony whereof I have signed my name to this specification in the presence of two subscribing witnesses.

WILLIAM F. AMBACH.
